UNITED STATES PATENT OFFICE.

FRANK R. CHASE AND ALBERT L. SIEBENTHALER, OF CINCINNATI, OHIO, ASSIGNEES
TO DANIEL W. McCARTHY, OF CINCINNATI, OHIO.

COIN-OPERATED WEIGHING AND VENDING MACHINE.

1,049,342.

Specification of Letters Patent.

Patented Jan. 7, 1913.

Application filed November 23, 1908, Serial No. 464,661. Renewed May 29, 1912. Serial No. 700,545.

To all whom it may concern:

Be it known that we, FRANK R. CHASE and ALBERT L. SIEBENTHALER, citizens of the United States, residing at Cincinnati, in the county of Hamilton and State of Ohio, have invented certain new and useful Improvements in Coin-Operated Weighing and Vending Machines, of which the following is a specification.

10 Our invention relates to coin operated weighing and vending machines. One of its objects is to provide a combined weighing and vending machine.

Another object is to provide improved 15 means for actuating and regulating the weight indicating pointer.

Another object is to provide improved adjustable means to regulate the movements of the pointer to register correctly upon the dial.

20 Another object is to relieve the pointer actuating mechanism from excessive strains, and to cushion its movements.

Another object is to provide improved means to prevent the weighing of more than 25 one person with a single coin.

It further consists in certain details of form, combination and arrangement, all of which will be more fully set forth in the description of the accompanying drawings, in 30 which,

Figure 1 is a front elevation of our improved mechanism. Fig. 2 is a perspective view of the coin receiving carriage or slide. Fig. 3 is a detail sectional view 35 through the coin receiving mechanism. Fig. 4 is a perspective view of the pointer locking lever detached. Fig. 5 is a rear elevation of the pointer actuating segment. Fig. 6 is a side elevation of the coin engaging 40 lever, detached. Fig. 7 is a side elevation of the lever transmitting motion from the coin receiving carriage to the vending mechanism. Fig. 8 is a section through the casing on line $x-x$ of Fig. 9 showing the operative 45 mechanism in front elevation. Fig. 9 is a section on line $v-v$ of Fig. 8, also showing the coin chute in section on line $y-y$.

In the accompanying drawings, A represents the frame or casing, A', the scale plat-

form, a, the pointer indicating the weight on 50 the dial, a'.

a^2 represents the coin receiving slot, a^3 , the opening or tray into which the articles to be vended are discharged and a^4 the lever which upon the introduction of a coin is enabled to release the pointer and discharge an article to be vended. Upon entering the slot, a^2 , the coin slides down the chute, a^6 , and drops between the slotted plates, b^1 , b^2 , resting upon the lever, C. The plate, b^2 , is carried by a carriage or slide, B, moving in ways, b^3 , in stationary frame, D, which carries the stationary plate, b^1 , and also serves to journal the shaft or rod, c, which carries the lever, C, and the lever, a'. The levers, C 65 and a' are normally held in the retracted position by a spring, e', attached at one end to the lever, C, which holds carriage, B, retracted by the engagement of lever, C, with its rear edge. The forward movement of lever, a', is limited by a stop pin, a⁸, and the forward movement of lever, a', carries with it the lever, C, which with a coin in position presses the plate, b^2 , and carriage, B, forward, and as soon as lever, a', is released, the 75 coin drops through carriage, B, and frame, D, into a coin receiver, not shown. In the absence of a coin, lever, C, passes through the slot of plate, b^2 , without moving carriage, B. Loosely mounted on shaft, c, is a 80 bell crank lever, E, the upper end of which engages a recess, e, in the carriage, B, so that the forward movement of carriage B tilts lever E. To the opposite end of lever, E, is connected a link, e', which in turn actuates a bell crank lever, F, to rock shaft, f. The opposite end of lever, F, and a crank arm, f', at the opposite end of shaft, f, engage between ears, f², f³ of a sliding plate, G, which is thereby actuated to slide beneath 85 the hopper, G, and has a recess, g, to receive and successively deliver packages, g', of chewing gum or other articles to be vended into the delivery tray, a⁹, through the recess, g². The rock shaft, f, by engaging opposite ends of plate, G, insures a uniform 90 and reliable movement of plate, G.

The pointer, a, is actuated by weight ap-

plied to the scale platform, A' by means of link or arm, H, attached at one end to one or more levers such as usually employed to support the scale platform of weighing mechanism, and at the opposite end to a spring, h, stationarily supported at its opposite end; thus weight applied to the scale platform will draw down arm, H, and extend or lengthen spring, h, in proportion to 10 the amount of weight applied.

The eye bar h' threaded to arm H enables adjustment to be made between arm H and spring h. The pointer a is pivotally supported on a shaft i' journaled in a bracket i of plate I. Shaft i' carries a pinion I' which meshes with and is driven by a segment J pivotally supported upon a stud j which is carried by a bracket J' which bridges the spring h. The segment J carries an arm K which normally engages a notch k in a pivoted locking bar K', to lock the pointer to zero position until released by the introduction of a coin, which release is effected by the plate b² engaging the lower 25 end k' of bar K' to tilt the bar and release arm K. The arm K is also adapted to engage any one of the teeth k² of bar K' after the coin has been released by lever C to prevent the pointer being shifted to a new position in an attempt to weigh more than one 30 person with a single coin. Segment J also carries a slotted arm L to which is attached a head L' adjustable within the limits of the slot l by means of a thumb screw l' 35 threaded into the end of arm L and pivotally attached to head L'. The arm L is normally held in the position Fig. 8 by a spring l² attached to an ear on arm L which throws segment J over into contact with the 40 screw l³ which serves as a stop and can be adjusted to bring the pointer over the zero mark on the dial. A pivoted cylinder M and plunger m attached to arm L serve to 45 pneumatically cushion the movement of the pointer in either direction when the weight is suddenly applied or removed from the scale platform.

A spring N stronger than spring l² is attached at one end to the arm H and at the 50 opposite end to an ear projecting from the adjustable head L'. This spring as the arm H moves downwardly yieldingly and mildly pulls upon the arm L without moving the arm L until after the coin is released when 55 it moves the arm L and rotates the pointer to indicate the weight on the scale platform. The adjustment of the head L' on arm L shifts the pull of spring N or from the axis of segment J and serves as a delicate means 60 to conveniently and readily standardize the scale, or cause the pointer to move the requisite distance over the dial to accurately indicate the weight, and also to re-

adjust the same from time to time as required. 65

A toothed crank arm P carried rigidly on shaft c is engaged by a spring actuated pawl p to prevent the coin being released at any thing less than a full movement of the lever a⁴. 70

The mechanism herein illustrated and described is capable of considerable modification without departing from the principle of our invention.

Having described our invention what we 75 claim is:

1. In a mechanism of the character described, a weight indicating pointer, a pivotally supported arm adapted to move said pointer, mechanism connected to said pivotally supported arm to yieldingly hold the pointer to zero position, a member adjustable on said arm, a member movable in proportion to the weight upon the scale, a yielding connection between said two last mentioned members, a member to hold said pivotally supported arm and pointer in position to record the weight, and means to release 85 said holding member. 90

2. In a mechanism of the character indicated, a weight indicating pointer, an arm adapted to move said pointer, a locking member adapted to engage said arm and through said arm to normally lock said pointer to zero position and also adapted to lock the pointer through said arm to position to record the weight on the scale, mechanism to release said locking member, a member adjustable on said pointer moving arm, a member movable in proportion to 95 the weight upon the scale, a yielding connection between said two last mentioned members, and means to return said pointer moving arm and pointer to initial position. 100

3. In a mechanism of the character indicated, a weight indicating pointer, a pivoted arm adapted to move said pointer, means to yieldingly hold said pointer and pivoted arm to initial position, a member adjustable on said pointer moving arm, a member movable in proportion to the weight upon the scale, and a yielding connection between 105 said two last mentioned members. 110

4. In a mechanism of the character described, a weight indicating pointer, a pivotally supported arm adapted to move said pointer, means to yieldingly hold said pointer and pivotally supported arm to initial position, a member movable in proportion to the weight upon said scale, a yielding connecting member attached to said pointer moving arm, a locking member adapted to lock said pointer moving arm to different positions, and mechanism to release said locking member. 115 120

5. In a mechanism of the character indi-

cated, a weight indicating pointer provided with a pinion, a pivotally supported arm provided with a segmental gear in mesh with said pinion and adapted to move said pointer, a member movable in proportion to the weight upon the scale, a yielding connecting member attached to said last mentioned member and adjustably connected to said pointer moving arm, means to lock said pointer moving arm with the pointer at

various positions, and mechanism to release said locking means.

In testimony whereof we have affixed our signatures in presence of two witnesses.

FRANK R. CHASE.

ALBERT L. SIEBENTHALER.
